YARN WINDING

Odell T. Brown, Old Hickory, Tenn., assignor to
 E. I. du Pont de Nemours & Company, Wil-
 mington, Del., a corporation of Delaware

Application October 3, 1940, Serial No. 359,539

5 Claims. (Cl. 242—39)

This invention relates to machines for the winding of thread, yarn and other strand-like materials into cones, cops, or similar types of packages. More particularly, the invention relates to an improved means of automatically stopping the action of such winding machine when the cone or other package has reached the desired size.

When winding yarn and other strand-like materials into packages, it is desirable that the winding mechanism be provided with a means to automatically stop the winding action when the cone package has reached the desired size. It is further desirable that the means be adjustable so that various size packages may be wound in an automatic manner.

The present invention is particularly directed to winding machines of the type wherein the yarn is wound upon a supporting element, such as a core, mounted upon a rotating spindle, the yarn being traversed longitudinally of the core by a thread guide that bears against the surface of the core, or the wound layers of yarn, and which recedes from the spindle as the wound package increases in size. The thread guide is mounted for reciprocation in a traverse frame, the latter being pivoted about a central shaft so as to permit this outward movement of the thread guide. The traverse frame is further fitted with a dogging lever adapted to ride in a groove formed in a segment pivoted upon the main frame of the machine. This dogging lever and grooved segment cooperate to direct the segment and thread guide in its outward movement with respect to the winding spindle and also to hold the guide from moving toward the spindle during the winding operation. Thus, these devices keep the guide from jumping or vibrating during the winding operation and prevent the guide from gouging into the package during the winding operation.

Such a winding machine is manufactured by the Universal Winding Company and is of the type known as "The #50 Universal Winding Machine." It is described in a general way in U. S. Patent No. 801,941 to Wardwell. As shown therein, the machine is provided with a starting lever mounted on a shaft extending to the back of the machine and adapted to engage the driving mechanism. The starting lever is fitted on one side with a braking means adapted to press against the spindle and thus prevent its rotation when the lever is in the "stop" position. The lever is fitted on the other side with an arm provided with a hook. When the starting lever

5 is in the "running position," this hook engages a second hook, fitted to the pivoted, grooved segment of the dogging device. Thus, these hooks act as a detent means to keep the starting lever in the "running position" and thus assure the continued operation of the winding machine. Raising the free end of the grooved segment releases the hooks from engagement with each other and permits the starting lever to return to 10 its original or "stop" position, thus halting the winding operation.

In the past, this raising of the free end of the segment has been effected by means of a member mounted in an adjustable manner along 15 the length of the segment and having a beveled undersurface adapted to be contacted by a portion of the traverse frame. As the package is built up, the traverse frame advances toward and finally contacts the beveled member mounted upon the segment. This continued motion of 20 the traverse frame against the beveled member serves to gradually lift the segment and release the starting lever, thus stopping the winding operation.

25 This device operates in a fairly satisfactory manner to effect the stopping of the winding operation. However, the traverse frame moves very slowly and, therefore, it lifts the segment very slowly with the result that it is difficult to obtain 30 the desired precision in the stopping of the winding operation and successive packages vary somewhat in their yarn content.

A still more serious defect of this device rests 35 in the fact that the beveled member serves to gradually retard the continued motion of the traverse frame and thus causes the thread guide to be pressed progressively more tightly against the package being wound. Hence, the yarn at the outside of the package is wound more tightly and firmly than the yarn at the inside of the package. Since it is desirable for cone packages to be evenly wound throughout their length, this is quite objectionable.

40 It is an object of this invention to provide an improved form of device for automatically stopping the action of a winding machine when the package being wound has reached the desired size.

45 It is also an object of this invention to provide a device of this type which may be accurately adjusted to permit the winding of various size packages of yarn or other strand-like material.

50 It is another object of this invention to provide a device of this type that will not cause the

outer layers of yarn to be wound more tightly than the inner layers, thus assuring the formation of a package that is wound evenly throughout its entire length.

Other objects of the invention will appear hereinafter.

The objects of this invention are accomplished, in general, by positioning a stop on the free end of the pivoted segment of a winding machine which stop will be suddenly contacted by an enlargement on the reciprocating traverse bar of the thread guide as it, together with the traverse frame, moves from the spindle during the winding operation. In accordance with the principles of this invention, a projection on the traverse bar strikes the stop with a forceful blow that serves to instantaneously lift the pivoted segment and thus stop the action of the winding machine. This sudden, forceful blow is in contrast to the slow and continued pressure exerted against the stop by the movement of the advancing traverse frame of the prior art, and constitutes an important feature of the invention.

The following written description of the invention will be made more readily understandable when taken in connection with the accompanying illustrations, in which:

Figure 1 is an end elevational view of a winding machine fitted with the device of this invention.

Figure 2 is a side elevational view of the winding machine shown in Figure 1.

Figure 3 is a side elevational view of a grooved segment having mounted thereon a stop means for lifting the segment.

Figure 4 is a side elevational view similar to Figure 3 showing another form of stop means.

Figure 5 is an enlarged end elevational view of the stop means shown in Figure 3.

Referring to the winding machine illustrated in Figures 1 and 2 of the accompanying drawings, reference numeral 1 designates the fixed main frame of the machine. At the top of frame 1, a rotating spindle 2 is journaled in bearings and adapted to be driven by means of a belt pulley or other suitable mechanism (not shown). The spindle is of usual form and is adapted to receive a cone or cop tube 3 on which the package 4 is to be wound.

A cam shaft 5 is journaled in roller bearings in the frame 1 and extends parallel with the winding spindle 2. The shaft 5 is connected to the spindle and is driven therefrom by suitable means, such as belt pulleys or gears not herein shown. The cam shaft 5 carries a helical grooved cam 6 (see Figure 2) of usual type which causes the thread guide 7 to reciprocate in a manner to be later described.

The thread guide 7 is mounted on a transverse bar 8. The traverse bar 8 is slidably positioned in a groove in an oscillating traverse frame 9. The traverse frame 9 comprises a suitable arm 10 which is pivoted to rock about the cam shaft 5. The overhanging front end of the frame 9 forms a horizontal arm or member 11 which is slotted and grooved longitudinally thereof to provide an extensive bearing for the reciprocable traverse bar 8, (see Figure 3). The traverse bar 8, to which is fixed the thread guide 7, is thus mounted to slide in a path extending substantially parallel to the axis of the winding spindle 2. The traverse bar 8 is connected at its inner end to a slide or cross head 13 which carries a pin or roller 14, the latter engaging the helical groove in the traverse cam 6.

A sheet metal back 15 is fastened to the traverse frame 9 and forms a rest or support for the upper portion of the thread guide 7. The thread guide comprises a metal holder whose lower end 5 is attached to and supported by the outer end of the traverse bar 8. The upper end of the holder is fitted with a circular head of metal or porcelain which is provided with a slotted opening through which the yarn, thread or other structure is directed to the yarn supporting element 3.

The traverse frame 9 is provided at its lower end with a counter-balance 16 which normally tends to swing the upper part of the frame toward the spindle 2 to hold the thread guide 7 in close contact with the yarn supporting element or with the layers of wound yarn. A dogging mechanism comprising a grooved segment, or sector, 17 and a lever 18 acts to maintain the position of the traverse frame as it advances from the spindle 20 and thus prevent the thread guide from gouging into the package. The segment is pivoted at 19 on the main frame 1 of the machine, and the lever 18 is pivoted on the traverse frame 9. The lever 18 rides in the groove of the segment as 25 shown in Figure 1.

The operation of the winding machine is controlled by a starting lever or handle 25, mounted on one end of a rotatable rod 26, the latter being supported in bearings at the top of the main frame 1. The opposite end of the rod 26 carries means (not shown) for operating a clutch or similar device to control the operation of the spindle and the other parts of the machine driven therefrom. The starting lever is provided on one 30 side with a braking means 27 which is adapted to press against the spindle and stop the rotation thereof when the lever is in the "stop position." The starting lever is provided on the other side thereof with a curved arm 28, the latter is fitted 35 with a hook member 29. When the lever 25 is in the running position, this hook 29 engages a similar hook 30 fitted to the pivoted segment 17 of the dogging device. These hooks, when engaged, act as a detent means to hold the starting lever in the running position.

When the starting lever is in the running position, all that is necessary to stop the winding action is to raise the free end of the pivoted segment 17 so that the hooks 29 and 30 of the detent 50 means will disengage and permit the starting lever to return to the "off position." The spring 55 aids in effecting this return of the lever.

As seen most clearly in Figure 2, the outer portion of the traverse bar 8, supporting the thread guide 7, is of heavier construction than the inner portion so that the rod possesses a shoulder 31 midway along its length. Inasmuch as the traverse bar is positioned to slidably reciprocate in the horizontal arm 11 of the traverse frame 9, the bar swings away from the spindle as the cone or other package is built up in diameter and thus the bar 8 advances, during the winding operation, with the traverse frame 9 toward the free end of the grooved segment 17 of the dogging device.

A stop member 32 is fixed to the free end of pivoted segment 17. The stop member is provided with a projection 40 which extends a sufficient distance below the segment that it will contact with shoulder 31, or any similar projection, 60 on the traverse bar 8 when the latter is oscillated, together with the traverse frame 9, to a position underlying the shoulder or projection.

As shown most clearly in Figures 3 and 4, the stop member 32 is preferably formed with a beveled lower surface, the beveled edge being sub-

stantially tangent to the curvature of the shoulder 31. Thus, the shoulder of the reciprocating traverse bar on striking this surface will readily lift the pivoted segment 17 and release the engaging hooks of the detent means and thus stop the operation of the machine.

According to the preferred embodiment of the invention, the stop member 32 is of the form shown most clearly in Figure 3. As seen therein, the member 32 is adjustable along the length of the pivoted segment 17, and comprises a U-shaped portion 48 fitted with 2 offset elements, contact element 40 and adjusting element 46, which extend along the lower and upper surfaces of the segment 17. The lower, beveled contact element 40 is adapted to be struck by the shoulder 31 of the advancing reciprocating traverse rod 8. The upper adjusting element 46 is fitted with a set screw 42, which serves to position the member 32 firmly at any point along the segment, the point being so chosen that the contact element will be struck by the traverse bar at that moment when the package has been wound to the desired size. The adjusting element 46 is further provided with a second set screw 44 that serves to raise or lower the beveled contact element 40 so that a more accurate adjustment of the member with regard to the traverse rod 8 can be made along the segment. The horizontal arm 11 as shown in Figure 3 illustrates the slotted and grooved construction of this member serving to support the traverse rod 8.

Referring to Figure 4 of the drawings, the stop member 32 comprises a collar 35 with a single set screw 42 whereby the member may be adjustably positioned at any desired point along the segment. A projecting contact element 45 is fastened to that portion of the collar 35 which underlies the segment 17. This modified form of stop member differs from the preferred member in that it is provided with only one set screw. Hence, the finer adjustment made possible by the device of the preferred embodiment cannot be obtained. However, it is possible to obtain a sufficiently fine adjustment to make the device operable and, in fact, it is possible to more accurately control the stopping of the winding action with this device than with any of the devices of the prior art. This device, like the device of the preferred embodiment, possesses the advantage that the grooved segment of the dogging device is lifted by means of a sharp, forceful blow struck by the rapidly reciprocating traverse bar of the winding machine rather than by a slow continued pressure exerted by the movement of the traverse frame of the winding machine. The member 32 can be formed in one piece or if desired the contact element 40 can be formed as a separate part, and be held in position against the under edge of the segment by the clamping action of a clamping collar or the like.

The present invention has been described above with detailed reference to the cooperative action between the reciprocating traverse bar and a stop member on the free end of the pivoted segment, or sector. The tripping of the segment to release the braking mechanism may be accomplished by any cooperative striking means on the segment and the reciprocating mechanism. For example, a stop member may be positioned on the segment which member will be struck by the reciprocating crosshead 13 shown in Figure 1. In its broad aspects, this invention contemplates the sudden striking of the seg-

ment, to trip the braking mechanism, by the rapidly moving reciprocating mechanism rather than by the slowly moving traverse frame.

This invention provides a method and apparatus for automatically stopping the action of a winding machine when the package being wound has reached the desired size.

The device provided by this invention results in the formation of a yarn package that is evenly wound throughout. The outer layers of yarn of such a package are not wound more tightly than are the inner layers.

The device provided by this invention acts in a much shorter period of time to stop the action of a winding machine than do other devices known to the art.

The invention thus provides an inexpensive, easily and accurately adjustable method of stopping the action of a winding machine at the exact moment the package being wound has reached the desired size.

Since it is obvious that many changes and modifications can be made in the above-described details without departing from the nature and spirit of the invention, it is to be understood that the invention is not to be limited to the said details except as set forth in the following claims.

I claim:

1. In a winding machine, a winding spindle, a braking mechanism for said spindle, a swinging traverse frame, a reciprocating yarn traversing mechanism connected to said traverse frame, a pivoted segment for controlling the movement of the traverse frame, brake detent means releasably connected between said braking mechanism and said segment, and a stop member positioned on said segment to lie in the path of said reciprocating yarn traversing mechanism, said traverse mechanism adapted to engage said stop member to release said brake detent means when the traverse frame is in a given position,

2. In a winding machine, a winding spindle, a braking mechanism for said spindle, a swinging traverse frame, a reciprocating yarn traversing mechanism connected to said traverse frame, a pivoted segment for controlling the movement of the traverse frame, brake detent means releasably connected between said braking mechanism and said segment, a stop member, comprising a contact element, positioned on said segment with the contact element lying in the path of said reciprocating yarn traversing mechanism, said traverse mechanism adapted to engage said contact element to release said brake detent means when the traverse frame is in a given position, and means on said stop member for adjusting said contact element.

3. In a winding machine, a winding spindle, a braking mechanism for said spindle, a swinging traverse frame, a reciprocating yarn traversing mechanism, comprising a traverse bar, connected to said traverse frame, a projection on said traverse bar, a pivoted segment for controlling the movement of the traverse frame, brake detent means releasably connected between said braking mechanism and said segment and a stop member positioned on said segment to lie in the path of said projection, said projection adapted to engage said stop member to release said brake detent means when the traverse frame is in a given position.

4. In a winding machine, a winding spindle, a braking mechanism for said spindle, a swinging traverse frame, a reciprocating yarn traversing

mechanism, comprising a traverse bar, connected to said traverse frame, a shoulder on said traverse bar, a pivoted segment for controlling the movement of the traverse frame, brake detent means releasably connected between said braking mechanism and said segment, and a stop member positioned on said segment to lie in the path of said shoulder, said shoulder adapted to engage said stop member to release said brake detent means when the traverse frame is in a given position.

5. In a winding machine, a winding spindle, a braking mechanism for said spindle, a swinging traverse frame, a reciprocating yarn traversing mechanism, comprising a traverse bar, connected to said traverse frame, a curved shoulder on said

traverse bar, a pivoted segment for controlling the movement of the traverse frame, brake detent means releasably connected between said braking mechanism and said segment, a stop member positioned on said segment, a contact element on said stop member, said contact element provided with a beveled edge substantially tangent to the radius of curvature of said shoulder, said stop member positioned with the beveled edge of said contact element lying in the path of said shoulder, said shoulder adapted to engage the beveled edge of said contact element to release said brake detent means when the traverse frame is in a given position.

15

ODELL T. BROWN.
